UNITED STATES PATENT OFFICE

GEORGE CARLETON, OF DETROIT, MICHIGAN

DESIGN FOR A COMBINED WEIGHING SCALE, CLOCK, AND ADVERTISING PANEL

Application filed October 18, 1930. Serial No. 37,315. Term of patent 7 years.

To all whom it may concern:

Be it known that I, GEORGE CARLETON, a citizen of Canada, residing at Detroit, in the county of Wayne and State of Michigan, have invented a new, original, and ornamental Design for a Combined Weighing Scale, Clock, and Advertising Panel, of which the following is a specification, reference being had to the accompanying drawing forming part thereof.

Fig. 1 shows a front elevation view of the article.

Fig. 2 shows a side elevation view of the article.

Fig. 3 is an enlarged view of a portion of Fig. 1.

Figs. 1 and 3 show a clock face disposed in a vertical trapezoidal panel, the numerals and hands being omitted from the showing of Fig. 1 because of their smallness.

The rear of the device is not shown, since it is plain or conventional.

What I claim is—

The ornamental design for a combined weighing scale, clock, and advertising panel, substantially as shown and described.

GEORGE CARLETON.
